COMBINED SERVING BOWL AND CLOSURE OR THE LIKE

Jack V. Croyle, Woonsocket, and Harold P. Ashton,
Providence, R.I., assignors to Dart Industries Inc., Los Angeles, Calif.

Filed July 22, 1971, Ser. No. 165,433

Term of patent 14 years

Int. Cl. D7—01

U.S. Cl. D7—18

FIG. 1

FIG. 2

FIG. 3

FIG. 4

FIG. 5

FIG. 1 is an exploded top perspective view of a combined serving bowl and closure or the like showing our new design;

FIG. 2 is a bottom view of the closure member thereof;

FIG. 3 is a front elevational view of the bowl member thereof;

FIG. 4 is a side elevational view of the bowl member thereof; and

FIG. 5 is a bottom view of the bowl member thereof.

We claim:

The ornamental design for a combined serving bowl and closure or the like, substantially as shown.
